(57) **CLAIM**

The ornamental design for a gridwall panels display stand, as shown and described.

DESCRIPTION

FIG. 1 is a top, front perspective view of the first embodiment of a gridwall panels display stand, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged view of detail 8 in FIG. 1; and,

FIG. 9 is a front view of the second embodiment of a gridwall panels display stand.

All the broken lines in the drawings depict portions of the gridwall panels display stand that form no part of the claimed design.

1 Claim, 8 Drawing Sheets
